UNITED STATES PATENT OFFICE.

JESSE A. BEAN, OF TEXARKANA, TEXAS, ASSIGNOR OF ONE-HALF TO CHARLES R. MONTGOMERY, OF TEXARKANA, TEXAS.

WRENCH.

1,140,018.

Specification of Letters Patent.

Patented May 18, 1915.

Application filed December 8, 1913. Serial No. 805,413.

To all whom it may concern:

Be it known that I, JESSE A. BEAN, a citizen of the United States, residing at Texarkana, in the county of Bowie and

5 State of Texas, have invented a new and useful Wrench, of which the following is a specification.

The invention relates to improvements in wrenches.

10 The object of the present invention is to improve the construction of wrenches, and to provide a simple, practical and inexpensive combined nut and pipe wrench of strong and durable construction, capable of 15 easy and quick adjustment and having its parts practically incased so that there will be nothing exposed and liable to get out of order by rough handling.

With these and other objects in view, the 20 invention consists in the construction and novel combination of parts hereinafter fully described, illustrated in the accompanying drawing, and pointed out in the claim hereto appended; it being understood 25 that various changes in the form, proportion, size and minor details of construction, within the scope of the claim, may be resorted to without departing from the spirit or sacrificing any of the advantages of the 30 invention.

In the drawing:—Figure 1 is a side elevation of a combined pipe and nut wrench, constructed in accordance with this invention. Fig. 2 is a central longitudinal sectional view of the same. Fig. 3 is a longitudinal sectional view of a portion of the wrench, taken at right angles to Fig. 2. Fig. 4 is a transverse sectional view on the line 4—4 of Fig. 2. Fig. 5 is a detail sectional view on the line 5—5 of Fig. 2. Fig. 6 is a detail perspective view of the toothed plate of the relatively fixed nut engaging jaw of the handle.

Like numerals of reference designate corresponding parts in all the figures of the drawing.

In the accompanying drawing in which is illustrated the preferred embodiment of the invention, 1 designates a hollow handle forming a longitudinal opening 2 for the reception of shanks 3 and 4 of relatively slidable nut and pipe engaging jaws 5 and 6. The handle is enlarged at its terminals to form relatively fixed inner jaws 7 and 8, 55 arranged to coöperate with the movable

jaws 5 and 6. The shank 3 of the nut engaging jaw 5 is adapted to slide freely in the longitudinal opening of the handle, and it is provided with a threaded inner portion 9 preferably flattened at the side faces, 60 as shown, and engaged by a rotary nut 10. The nut 10, which is substantially cylindrical, has its outer face checkered or otherwise roughened to enable it to be readily gripped, and it is provided with interior 65 threads 11 for engaging the threaded portion 9 of the shank 3. The nut 10, which is mounted in a transverse opening 12 in the handle at the central portion thereof, projects slightly at the side faces of the said 70 handle to enable it to be easily grasped and operated.

The shank 4 of the pipe engaging jaw 6 has its inner end 13 bifurcated to receive the inner end 14 of the shank 3, which is 75 reduced at the said inner end 14 to fit in the bifurcation of the shank 4, and it is pivotally connected to the same by a screw 15, or other suitable fastening device, which is arranged in registering perforations of the 80 said shanks. The handle is provided at opposite sides of its longitudinal opening or passage with aligned transverse holes 16 of a size to permit the screw 15 to be readily passed through them, whereby when the 85 screw is brought opposite the holes, it may be readily placed in position or removed therefrom. The openings also will enable a pin or rivet to be driven in or out of the transverse perforations of the shanks when 90 a pivot of this character is employed. The pivot permits the shank 4 and the nut engaging jaw 6 to oscillate within an inwardly tapered enlarged portion 17 of the longitudinal opening of the handle 1. The opening is enlarged at the back, the front wall being straight and the shank 4 being maintained normally in parallelism therewith by a spring 18, secured by a screw 19 in a recess 20 in the rear edge of the hollow handle. 95 The spring, which has a free outer end, is bent inwardly at right angles to form an outer arm 21, which extends through a slot 22 in the back of the handle and engages the rear edge of the shank 4.

The outer pipe engaging jaw 6 is provided at its inner engaging face with inwardly shouldered teeth 23, and the inner pipe engaging jaw 8 is equipped with a toothed plate 24 having outwardly shoul- 110

2

dered teeth 25 to coöperate with the teeth 23 in gripping a pipe or rod. The toothed plate 24, which is mounted in a recess 25 of the jaw or enlargement 8, is provided with 5 a central longitudinal rib 26, extending along the inner face of the toothed plate and provided at the back with an extension 27. The rib 26 with its extension is arranged in a corresponding groove in the jaw or enlargement 8, and it is pierced by a transverse pin 28, which extends through the jaw enlargement 8. In operating upon a pipe or rod, the handle is moved forwardly to cause the jaws to grip the said pipe or 10 rod, and a backward movement of the handle operates to release the pipe or rod and will enable the wrench to obtain a new hold on the same.

The nut operates the relatively movable 20 jaws, which are simultaneously actuated in the same direction, the sliding movement of the shanks producing an opening movement of the jaws at one end of the wrench and a closing movement of the jaws at the 25 other end of the wrench.

This construction provides a well balanced wrench, which is adapted to be easily operated and effect a material saving in time and obviating the necessity of employing 30 separate pipe and nut wrenches.

What is claimed is:—
A wrench of the class described including

a hollow handle having a longitudinal opening extending entirely through it and enlarged at one end, said handle being provided at a point intermediate of its ends with a transverse opening and having its terminal portions enlarged to form inner 35 relatively fixed jaws, outer relatively slide- able jaws having shanks extending into the longitudinal opening from the opposite ends thereof, the shank of one of the jaws being relatively long and provided with a threaded portion and extending inwardly beyond the transverse opening, the shank of the 40 other outer jaw being relatively short and pivotally connected to the threaded shank and adapted to oscillate in the enlarged end of the longitudinal opening of the handle, an 45 adjusting nut operating in the transverse opening of the handle and engaging the threads of the relatively long shank, and an exteriorly arranged spring piercing the hollow handle at the enlarged portion of the longitudinal opening and bearing against 50 the said relatively short shank.

In testimony, that I claim the foregoing as my own I have hereto affixed my signature in the presence of two witnesses.

JESSE A. BEAN.
